UNITED STATES PATENT OFFICE

1,978,328

DENTAL FITTING FOR LAVATORIES

Lillian B. Roberts, Murfreesboro, Tenn.

Application May 17, 1934, Serial No. 726,142

6 Claims. (Cl. 4—263)

This invention relates to fittings for a lavatory and more particularly to a dental fitting to provide clean water and to remove waste water.

An object of this invention is to provide a fitting which is so constructed that water may be obtained for use in cleaning the teeth and the waste water may be discharged through the drain pipe of the wash basin to which the device is attached.

10 A further object of this invention is to provide a combination fitting which can be combined with a wash basin and connected to the source of water supply for the basin and also to the waste connection for the basin so that suitable water of desired temperature can be supplied at the desired point.

20 A still further object of this invention is to provide a fitting of this kind wherein the draining means for the wash basin also acts as the means for operating the valve embodied in the device so that the water may be supplied to either the basin or the spout.

The above and various other objects and advantages of this invention will in part be described and in part be understood from the following detailed description of the present preferred embodiment, the same being illustrated in the accompanying drawing wherein:

25 Figure 1 is a vertical section partly in detail of a device constructed according to the embodiment of this invention.

Figure 2 is a sectional view taken on the line 2—2 of Figure 1.

30 Figure 3 is a sectional view taken on the line 3—3 of Figure 1.

Referring to the drawing wherein like numerals of reference designate corresponding parts throughout the several views, the numeral 10 designates generally a basin provided with a base 11 which is mounted on a supporting member 13. The basin in the present instance is constructed with a relatively small central portion or stem 12, which terminates in a spout 14 extending horizontally from the base 11. The base 11 has a bore 15 extending vertically therethrough and a pipe 16 is threaded into the lower portion of the base and is locked as by a nut 17 to the spout 14. The pipe 16 is adapted to be connected to a source of water supply. The spout 14 has a channel or passage 18 communicating with the bore 15 of the base 11, so that the water from the pipe 16 will flow through the spout or neck 14. The basin 10 has disposed on one side thereof a channel or passage 19 which opens, as at 20, in the rim 21 of the basin and opens in the direction

of the body of the basin so that the water or liquid flowing upwardly in the channel 19 will be directed into the interior of the basin 10. The lower end of the passage 19 communicates with the bore 15 preferably at a point diametrically opposed to the channel 18 in the spout or spigot 14.

In order to regulate the flow of water or liquid through either the spout 14 or the passage 19, I have provided a substantially cylindrical valve 22 which is disposed in the bore 15. This valve 22 has an opening 23 which, upon turning of the valve 22 in one direction, is adapted to discharge the water from the pipe 16 into the channel 18. The valve 22 also has a second opening 24 which is adapted to permit, upon turning of the valve 22, the discharge of water into the passage 19. The lower end of the valve 22 preferably engages the upper end of the pipe 16 and the lower end is provided with an arcuate recess 25 in which is received a pin 26 secured to the base 10. The pin 26 acts as a limiting means to limit the turning of the valve 22 or permitting sufficient rotation thereof to bring the desired openings in the valve into register with the desired discharge channel. A flanged cap 27 is threaded into the lower portion of the basin 10 and engages the upper end of the valve 22 so as to hold this valve 22 against longitudinal movement in the bore 15 while permitting rotary movement. A gasket or washer 28 is interposed between the cap 27 and the upper end of the valve 15 so as to seal the valve in the lower portion of the basin 10.

The cap 27 has an opening 29 centrally therethrough in which a combined valve operating member and drain 30 is slidably and rotatably received. The valve operating and drain member 30 comprises a length of pipe substantially smaller in diameter than the pipe 16 and this hollow member 30 is provided with a knob or handle 31 on the upper end thereof.

The hollow drain member and valve operating member 30 at a point within the base 11, is provided with a plurality of outstanding radially arranged pins 32 which engage in vertical grooves 33 provided in the inner surface of the valve 22. These pins 32 permit vertical movement of the member 30 for a distance of substantially the length of the valve 22 so that the drain openings 34 in the upper end of the member 30 can be positioned at a point adjacent the upper surface of the cap 27 which constitutes the bottom of the basin 10 or the drain openings 34 may be raised to a point spaced upwardly from the bottom of the basin 10. In the raised position of the openings 110

34, the valve 22 is preferably closed as to the passage 19.

In the use and operation of this device, when it is desired to discharge water through the 5 spigot 14, the valve 22 is turned, as shown in Figures 1 and 2, so that the discharge opening 23 in the valve will register with the passage 18 in the spout 14. At this time, the passage 19 is closed so that no water will be discharged through 10 the passage 19. If it is desired to discharge water into the basin 10 through the passage 19, the valve 22 is turned so that the opening 24 will register with the lower end of the passage 19, thereby cutting off the passage 18. During the 15 use of the valve 22, the valve operating member and drain 30 may be either at the lowermost point shown in full lines in Figure 1, or may be raised to the point shown in dotted lines in Figure 1. Where the valve operating member and 20 drain 30 is at the lowermost point, all water received in the basin 10 will flow out through the drain openings 34 and down through the pipe 30 which is adapted to be connected to a suitable carry-off pipe.

25 The valve operating member 30 in the present instance also operates the drain plug connected to the wash basin on which the basin 10 hereinbefore described is mounted. Preferably, the support 13 is the top or rim of the wash basin and 30 the valve operating member 30 is the vertically movable drain plug operating member used in the type of wash basins where the plug is raised by an operating member disposed at one side of the basin. It will, therefore, be apparent that 35 the drain plug operating member for the wash basin will also serve the purpose of providing a drain means for the basin 10 which is preferably constructed of the same design and material as the escutcheons on the lavatory handles.

40 It will also be apparent from the foregoing that the device hereinbefore described will increase the sanitation of the wash basin in that the basin 10 will provide a means for receiving the waste water during the washing of the teeth and 45 the rinsing of the mouth, whereas the wash basin proper may be used for washing of the face and hands.

What is claimed is:—

1. A fitting as set forth, comprising a base having 50 a passage therethrough, a basin extending above the base, means for connecting the base to a source of liquid supply, a two-way valve carried by the base, means carried by the basin and communicating with the passage in the base to discharge the liquid in the upper portion of the basin and valve operating means extending upwardly into the basin.

2. A fitting as set forth, comprising a base having 55 a passage therethrough, means for connecting the base to a source of liquid supply, a spout carried by the base and communicating with the passage therein, a basin extending above the base, means carried by the basin and communicating with the passage to discharge the liquid in the upper portion of the basin, a two-way valve carried by the base, and valve operating means extending upwardly into the basin.

3. A fitting as set forth, comprising a base having 60 a passage therethrough, means for connecting the base to a source of liquid supply, a basin extending laterally of the base and communicating with the passage therein, means carried by the basin for discharging the liquid in the upper portion of the basin, a two-way valve carried by the base, a hollow valve operating member extending upwardly through the basin, and means for connecting the valve operating member to a carry-off means.

4. A fitting as set forth, comprising a base having 65 a passage therethrough, a basin extending laterally of the base and communicating with the passage, means carried by the side of the basin and opening into the upper portion thereof for discharging the liquid in the upper portion of the basin, a two-way valve carried by the base and controlling the flow of liquid through the spout and the basin discharging means, a valve operating member extending upwardly into the basin, means for slidably connecting the valve operating member with the valve whereby to permit vertical movement of 70 the valve operating member, said valve operating member having a drain passage extending longitudinally therethrough, and an opening in the wall thereof adjacent the upper end and disposed within the basin to permit the draining of the liquid out of the basin, and a handle secured to the upper end of the valve operating member.

5. A fitting as set forth, comprising a base having 75 a passage therethrough, a basin extending laterally of the base and having a passage communicating with the passage in the basin, means carried by the side of the basin for discharging the liquid into the upper portion of the basin, a cylindrical valve member disposed in the base, said valve member having a pair of discharge openings therein, said valve member having a plurality of vertically extending grooves on the inside thereof, a hollow valve operating member disposed concentrically of the valve, radially disposed pins carried by 80 said valve operating member and loosely engaging in said grooves whereby to rotate said valve upon rotation of the valve operating member while permitting independent movement of the valve operating member longitudinally through the valve, said valve operating member having a drain 85 opening in the upper portion thereof and disposed within the basin whereby to permit the liquid in the basin to drain through the valve operating member, and a handle secured to the upper end of the valve operating member.

6. A fitting as set forth, comprising a base having 90 a passage therethrough, a basin extending above the base, means for connecting the base to a source of liquid supply, a two-way valve carried by the base, means extending through the valve 95 and the basin and communicating with the basin to carry off liquids in the basin, and means carried by said latter named means and engaging the valve for operation thereby.

140 LILLIAN B. ROBERTS.
